KNITTING MACHINE

William Needham, Arnold, England

Application June 3, 1942, Serial No. 445,608
In Great Britain April 4, 1941

2 Claims. (Cl. 66—8)

This invention is for improvements in and applicable to knitting machines and the production of fabric thereon.

Viewed from one aspect the invention consists in the provision of means for severing the float threads in fabrics produced on circular knitting machines by the employment of a gap of inoperative needles.

A particular feature of the invention consists in the production on a circular knitting machine of a stocking blank shaped by varying the number of inoperative needles in a gap of needles and cutting the float threads at each end of said gap during the production of the blank on the machine.

Viewed from another aspect the invention consists in the provision in or for a knitting machine of a knitting needle having means for cutting threads during the production of fabric on a knitting machine.

The invention is particularly, but not exclusively, concerned with latch needles, especially plural latch needles for the production of ladder-resistant fabric according to Patents No. 1,894,319 and 1,960,161.

The foregoing and other features of the invention set out in the appended claims are incorporated in the constructions which will now be described with reference to the accompanying drawings, in which

Figures 1-4 show four variants of cutter, applied to latch needles.

Figure 5 shows the knitting cams for use with the needles shown in Figs. 1-3.

Fig. 5A illustrates the knitting cams for use with the needle shown in Fig. 4.

Figure 6 shows the movements of a plural latch needle formed with a cutter, while

Figure 7 is a diagram of the cams for giving said movements.

According to one embodiment of this invention a hooked knitted needle 10 of the kind employed in knitting machines has a cutting or knife edge 11 formed on the front of its shank or stem 12 for the purpose of cutting a loop moved along said stem to an abnormal extent from the hook of the needle (the abnormal location of said loop being shown in dotted lines in Figs. 1-4). This cutting edge or knife edge 11 may extend substantially parallel to the rear edge of the needle as shown in Fig. 1 or it may extend obliquely upwards towards the rear of the needle. For example, as shown in Fig. 2, it may be formed on a swell or shoulder 13 whereat the depth of the needle stem 12 from front to rear increases

between that small dimension which is desirable at the location occupied by a normally cleared loop to that greater dimension which is desirable to provide an adequate guide for the needle in its trick. In a further alternative, Fig. 3, just below such a swell 13 there is a deep but narrow cleft 14 in the stem of the needle extending inwards from the front edge thereof and directed diagonally upwards (i. e. towards the hook) so as to form a thin beak 13' above said cleft. The cutting edge is formed either on the inner and lower edge 14a of this cleft 14 and/or on the upper and outer edge 14b thereof. That is to say it is formed either on the inner edge of the beak 13' or on the main part of the needle stem or on both. The tip of the beak 13' preferably projects towards slightly beyond the front edge of the main part (the lower wide part 12') of the stem.

In a still further construction, Fig. 4, at the root of the swell 13 there is a small throat or catch 15, the edges of which are formed as knife edges. Slightly nearer to the hook than this throat 15 a downwardly-directed latch 16 is pivoted, the said latch having a limited opening and closing movement. The tip of the latch projects forward slightly beyond the front edge of the broad part 12' of the needle stem. Therefore if a loop is cleared to an abnormal extent it passes on to this latch 16 and thence on to the broad part 12' of the stem, which abnormal clearing movement may be effected as is well known either by moving the loop or by moving the needle. If the loop is then caused to move in the reverse direction it passes under the latch 16 and by suitable manipulation may be caused to enter the catch 15 and to be severed.

An important application of the invention is to that type of circular knitting machine wherein fashioning of the blank is effected during rotation by varying the number of needles knitting at a certain locality in the needle bed so as to produce a divergent or convergent gap across which floating threads are normally laid. Such machines form the subject of Letters Patent Nos. 2,271,386 and 2,191,577. By the exercise of the present invention these floating threads may be cut out as they are formed. For example, each needle which functions as a selvedge needle at any phase during the formation of a fashioned blank may be provided with a cutting edge in accordance with this invention. At an appropriate time after the float thread has been formed in any one course, one needle at each side of the gap may be automatically selected and operated to cut the float thread. The particular

needles selected may be those two which at the time of cutting are functioning as selvedge needles, or they may be those needles next adjacent to the selvedge needles. Alternatively several needles at each side of the gap beyond the normal selvedge needles may knit part of the float thread in order to form what is in effect a false selvedge with a few wales of loops between the two selvedges. It will be appreciated that if, now, the yarn is cut by one of the needles intermediate each normal and false selvedge the yarn is controlled on both sides of the cut by adjacent needle loops. If desired, this cutting need not take place until the thread (or threads, in the case of the ladder resistant fabric) or a second course has been laid upon the needle.

Referring to Figure 5 which shows the conventional knitting cams of a seamless hose or half hose machine, the needles normally clear at cam 17, knit at stitch cam 71 and are raised by cam 18, during rotation. Prior to descending the stitch cam 71 the appropriate needles which are to cut their loops are selected and raised, by selecting mechanism of any appropriate kind to meet the additional cam 19. This cam raises the needles to an abnormal height; in the case of needles according to Fig. 1 or 2 the loops are thereby severed, while in the case of needles according to Fig. 3 the movement to the abnormal height clears the loop below the cleft 14. The said needles are then lowered by the additional cam 20 and in the case of needles as shown in Fig. 3 this results in the loops passing into the clefts 14 so that the loops are severed. In the case of a needle according to Fig. 4 the needle is only lowered slightly by additional cam 20' (Fig. 5A) so as to bring the loop underneath the latch 16. Said needle is then raised by additional cam 21 so that the loop is cut by the catch 15, and the needle is finally lowered by cam 22.

In the case of a plural latch needle for producing the fabric of the patent hereinbefore referred to, the ground or main thread and the locking thread are conveniently cut at about the stage whereat normally a loop of locking thread would be cast off over a loop of ground thread. For example, employing a needle with beak and cleft as hereinbefore described, after the needle has been raised to clear both threads below the latches, instead of being lowered, it is by selective mechanism given an additional upward

movement to clear the loops below the beak and is then lowered so that the loops are taken into the cleft and are cut.

Figure 6 shows at *a* to *e* the various stages in the foregoing operation, the said stages corresponding to the like lettered points in the cams shown in Fig. 7. These cams are in the main similar to those illustrated in patent specification No. 1,844,781 with the addition of cams 28 and 29. The plural latch needle shown in Fig. 6 has a cleft 14 and beak 13' as in Fig. 3. It is normally raised by cam 23 to clear the ground loop G below the latches, stage *a*, and is then lowered by cam 24 to bring the ground loop between the latches, stage *b*. Thereafter it is again raised by cam 25 to bring the ground loop below the bottom latch, both latches being open, and the locking thread L is fed across between the latches, stage *c*. In the normal operation of locking the ground loop G the needle is lowered by cam 26 to cause the ground loop G to be cast over the locking loop L into the hook of the needle and to cause the locking loop to be cast off, the needle being again subsequently raised by cam 27. If it is desired to sever the loops, at stage *c* the appropriate needle is selected to be engaged by the additional up-throw cam 28, which elevates it to stage *d* whereat both loops are cleared below the beak 13'. The needle is then lowered by additional cam 29 so that both loops pass into the cleft 14 and, as shown at stage *e*, are severed during the descent of the needle.

I claim:

1. In a knitting machine for producing a fashioned fabric blank by variations in the number of needles knitting at a certain locality to produce a divergent or convergent gap across which float threads extend, means for severing such threads during production of the fabric, comprising needles operating adjacent each edge of said gap, the stems of which are provided with a cutting edge disposed to be engaged by and to sever loops of the thread occupying an abnormal relation to such needles; and means for moving such needles to cause said abnormal relation and severance of said loops.

2. A circular knitting machine according to claim 1, wherein the severing needles are edge needles.

W. NEEDHAM.
